US0D1080767S

(12) **United States Design Patent** (10) **Patent No.:** **US D1,080,767 S**
(45) **Date of Patent:** **** Jun. 24, 2025**

(54) **EXERCISE BIKE**

(71) Applicant: **NetEase Youdao (Hangzhou) Smart Technology Co., Ltd.**, Zhejiang (CN)

(72) Inventors: **Pia Sofie Sollund**, Oslo (NO); **Andrea Ponti**, Hong Kong (HK); **Larry Tsai**, Hong Kong (HK); **Kim Rubin**, Menlo Park, CA (US)

(73) Assignee: **NetEase Youdao (Hangzhou) Smart Technology Co., Ltd.**, Zhejiang (CN)

(**) Term: **15 Years**

(21) Appl. No.: **29/773,074**

(22) Filed: **Mar. 5, 2021**

(51) LOC (15) Cl. **21-02**

(52) U.S. Cl.

USPC **D21/663**

(58) **Field of Classification Search**

USPC D21/662, 663, 664, 665, 666, 667, 694,

D21/697; D12/107, 111

CPC ... A63B 22/001; A63B 22/06; A63B 22/0605;

(57) **CLAIM**

The ornamental design for an exercise bike as shown and described.

DESCRIPTION

FIG. 1 is a first perspective view of the exercise bike;

FIG. 2 is a second perspective view of the exercise bike;

FIG. 3 is a third perspective view of the exercise bike;

FIG. 4 is a fourth perspective view of the exercise bike;

FIG. 5 is a top view of the exercise bike;

FIG. 6 is a side view of the exercise bike;

FIG. 7 is a rear view of the exercise bike; and,

FIG. 8 is a front view of the exercise bike.

The broken lines shown in the figures depict portions of the exercise bike that form no part of the claimed design.

1 Claim, 8 Drawing Sheets
